CLOSURE SEALING APPARATUS

David Stern, Newton, Mass.

Original application September 10, 1931, Serial
No. 562,065. Divided and this application June
13, 1932. Serial No. 617,034

9 Claims. (Cl. 113—18)

This invention relates to an apparatus for locking set-in covers in deformable containers in such manner that the same can not be removed without leaving evidence of tampering. This result is secured in the present case by a single movement of the crimping members which produces in the contacting cover flange and container wall interlocked horizontal lugs which extend from the material thereof either inwardly 5 or outwardly of the container wall, as appears in applicant's copending application, Serial No. 562,065, filed Sept. 10, 1931, of which the present is a divisional application.

In the accompanying specification, I have described, and in the drawing illustrated, an apparatus which has proven practical in use and produces a satisfactory seal of the cover in the container.

Fig. 1 is an elevation of my cover sealing apparatus in inoperative position.

Fig. 2 is a similar view showing the parts in operating position.

Fig. 3 is a view of the female die removed.

Fig. 4 is a bottom end view looking up at the same.

Fig. 5 is a fragmentary view of the male die removed, and

Fig. 6 is a bottom end view looking up at the same.

30 My machine for crimping the cover to the container wall, illustrated in the drawing, comprises a bottom frame member 10 which is connected to an upper frame member 11 by the rod 12 on which the member 11 is rigidly mounted and which itself is slidable in the member 10. On the upper end of the rod 12, is a handle 13 by means of which the member 11 is raised and lowered to operate the crimping dies 15 and 16. The rod 12 has an enlarged portion 12¹ at its lower end which 35 bears against the shoulders 10¹ on the member 10 to prevent disengagement of the handle 13, member 11, and rod 12 from the member 10.

On each extreme end of the lower face of the member 11 is mounted a wedge 14 having a vertical face 14³ and a beveled face 14⁴, one end of the base 14¹ of which wedge extends slightly beyond the extreme ends of the member 11. The point of the wedge 14 is cut off inwardly as at 14² to produce a beveled operating end 14⁵ adapted 40 to enter between the upper end of a female die 15 and an anti-friction roller 17 rotatably mounted in the upper end of the male die 16. The roller 17 materially decreases friction and permits a ready entry of the wedge between the dies. The 45 dies 15 and 16 adjacent but slightly above their

operating faces are pivotally mounted in the same plane in the member 10 which is slotted adjacent each end to receive the same and which serves as a fulcrum 18 on which the dies pivot as the operating portions thereof contact and deform the 60 container wall and cover to produce the lugs 6. The male die 16 is mounted so that its lugs 16² is aligned with the recess 15² of the female die 15.

The dies 15 and 16 when the wedge 14 is in raised or inoperative position are held in spaced 65 parallel position under the influence of the spring 19.

The female die, near its lower end, is cut away as shown at 15² of Figures 3 and 4 and the male die is provided at its lowermost end with a de- 70 forming lug member 16².

The female die near its upper end has a shoulder 15¹ on the operating side of the die. In inoperative position, the vertical side 14³ of the wedge and the female die 15 below the shoulder 75 15¹ are in substantial alignment, the short bevel 14⁵ bearing on the shoulder 15 (Fig. 1). As the beveled wedge faces 14⁴ and 14⁵ enter between the dies, the shoulder 15 passes from the bevel 14⁵ and engages the vertical face 14³ of the wedge 80 thereby moving the die 15 on its pivot and holding it slightly inwardly inclined so that its recess 15² is in position to receive the lug 16² of the male die. The long bevel 14⁴ as it penetrates progressively forces the upper end of the male die 85 16 outwardly and thereby forces the lower end with the lug 16² inwardly and upwardly toward the recess 15² and clinches the material of the interposed wall and cover flange to produce the lugs 6 therein. (See Fig. 2.) In operation, my 90 device is positioned over the container, as shown in Fig. 1. The handle 13 is lowered causing the dies to assume the position of Fig. 2, thus locking the cover of the can.

The crimping device may readily be removed 95 from the container simply by raising the handle 13 which carries with it the member 11, with the attached wedges 14, thus withdrawing the same from between the dies 15 and 16. Thus released the dies return to normal inoperative position 100 under the influence of the spring 19.

If additional lugs are desired, the crimping device may readily be re-positioned on the container and the above operation repeated. It will be apparent that the only steps to be taken by the 105 operator are the positioning of the device and the lowering and raising of the handle 13.

Various modifications in the construction and operation of my device may obviously be resorted to without departing from the spirit of my inven- 110

tion if within the limits of the appended claims.

I claim:

1. Mechanism for attaching a flanged cover to a wall container comprising a frame having a pair of spaced horizontal members, a pair of dies pivotally mounted on said lower member with their operating ends projecting therebeneath and adapted to be disposed one on each side of said cover flange and container wall, and their upper ends extending above said lower member, die operating means carried by said upper member and disposed so as to penetrate between the upper ends of said dies whereby said dies are rocked on their pivots and their operating faces forced inwardly to engage the container wall and cover flange to deform the material thereof so as to interlock the same.

2. Mechanism for attaching a flanged cover to a walled container comprising a frame having a pair of spaced horizontal members and a rod connecting the same, the upper member being fixed on said rod and said rod being slidable in said lower member, a pair of dies pivotally mounted on said lower member with their operating ends projecting therebeneath and adapted to be disposed one on each side of said cover flange and container wall, the upper ends of said dies extending above said lower member, die operating means carried by said upper member and disposed so as to penetrate between the upper ends of said dies whereby said dies are rocked on their pivots to force their operating faces inwardly to engage the container wall and cover flange to deform the material thereof so as to interlock the same.

3. Mechanism for attaching a flanged cover to a walled container comprising a frame having a pair of spaced horizontal members and a rod connecting the same, the upper member being fixed on said rod and said rod being slidable in said lower member, a pair of dies pivotally mounted on said lower member in spaced relation to each other with their operating ends projecting therebeneath and adapted to be disposed one on each side of said cover flange and container wall, the upper ends of said dies extending above said lower member, a spring connecting said dies and normally maintaining the same in parallel relation one to the other, die operating means carried by said upper member and disposed so as to penetrate between the upper ends of said dies whereby said dies are rocked on their pivots to force their operating faces inwardly to engage the container wall and cover flange to deform the material thereof so as to interlock the same.

4. Mechanism for attaching a flanged cover to a walled container comprising a frame having a pair of spaced horizontal members and a rod connecting the same, the upper member being fixed on said rod and said rod being slidable in said lower member, a pair of dies pivotally mounted on said lower member in spaced relation to each other with their operating ends projecting therebeneath and adapted to be disposed one on each side of said cover flange and container wall, the upper ends of said dies extending above said lower member, die operating means carried by said upper member and disposed so as to penetrate between the upper ends of said dies whereby said dies are rocked on their pivots to force their operating faces inwardly to engage the container wall and cover flange to deform the material thereof so as to interlock the same, and anti-friction means between said dies and said die operating means.

5. Mechanism for attaching a flanged cover to a walled container comprising a frame, a male die having a projecting lug and a female die recessed to receive said lug, said dies being pivotally mounted on said frame in spaced relation to each other and being adapted to be disposed one on each side of said cover flange and wall, a wedge operatively carried by said frame and adapted to enter between the upper ends of said dies, the inclined face of said wedge being adapted as it enters between said dies progressively to rock said male die on its pivot so as to drive the operating face thereof inwardly towards said female die so as to engage the container wall and cover flange therewith to deform the material thereof so as to interlock the same.

6. Mechanism for attaching a flanged cover to a walled container comprising a frame, a male die and a female die pivotally mounted therein and adapted to be disposed one on each side of said flange and wall, said male die having a projecting lug and said female die being recessed to receive said lug, an anti-friction roller at the upper end of said male die, a die operating member operatively carried by said frame and adapted to enter between the upper ends of said dies, and having an inclined face adapted to engage said anti-friction roller progressively to rock said male die on its pivot, so as to drive its operating face inwardly towards said female die and thereby to engage the container wall and cover flange therewith to deform the material thereof so as to interlock the same.

7. Mechanism for attaching a flanged cover to a walled container comprising a frame, a pair of dies pivotally mounted on said frame in spaced relation to each other and adapted to be disposed one on each side of said wall and cover flange, a die operating member carried by said frame, said member having a long bevel on one face and a shorter bevel on the opposite face, said operating member being adapted to enter between said dies above their pivoted points with its long bevel contacting one of said dies and its short bevel engaging the other die whereby both dies are rocked on their pivots, said die contacted by said long bevel being progressively rocked to an extent sufficient to drive said die inwardly towards said other die and thereby engage the material of said flange and wall disposed between said dies to deform said material so as to interlock the flange and wall.

8. Mechanism for attaching a flanged cover to a walled container comprising a frame, a male die and a female die pivotally mounted on said frame in spaced relation to each other and adapted to be disposed one on each side of said wall and cover flange, said male die having a projecting lug on its inner face and said female die being recessed to receive said lug, said male die being horizontally mounted on said frame so that said lug is aligned with said recess, means for operating said dies comprising a member mounted on said frame and adapted to enter between said dies to separate the upper ends thereof and to drive the operating ends thereof toward each other whereby to engage and deform the material of the cover flange and container wall so as to interlock the same.

9. Mechanism for attaching a flanged cover to a walled container comprising a frame, a pair of dies pivotally mounted on said frame in spaced relation to each other, and adapted to be disposed one on each side of said wall and cover

flange, means for operating said dies comprising a member disposed normally above the upper ends thereof, said member having a straight side and a beveled side, said straight side being aligned with the operating face of said female die during inoperative position, said die near its upper end having a shoulder, said shoulder being adapted to engage the straight side of said wedge to rock said die on its pivot so as slightly to

incline the same from the vertical, said inclined face of said wedge engaging the upper end of said male die and progressively forcing its upper end outwardly and its operating end inwardly toward the said female die so as to engage and deform the material of said flange and container wall so as to interlock the same.
